UNITED STATES PATENT OFFICE.

DAVID R. SAUNDERS AND JACOB M. LEE, OF HOUSTON, TEXAS.

DESIGN FOR A REIN-HOLDER.

SPECIFICATION forming part of Design No. 27,754, dated October 19, 1897.

Application filed August 30, 1897. Serial No. 650,061. Term of patent 7 years.

To all whom it may concern:

Be it known that we, DAVID R. SAUNDERS and JACOB M. LEE, citizens of the United States, residing at Houston, in the county of Harris and State of Texas, have invented a new and original Design for a Rein-Holder, of which the following is a specification.

This invention relates to a new and original design for a rein-holder; and it has for its object to provide a design of this character that shall be both useful and ornamental.

The leading feature of the design resides in a body having a longitudinally-curved base-piece provided at its ends with opposite 15 duplicate substantially **U**-shaped bends continued into reversely-disposed ovoidal loops lying in the same plane as the **U**-shaped bends and having terminal extensions provided with looped feet lying substantially in 20 the longitudinal plane of said base-piece.

A minor feature of the design resides in providing the longitudinally-curved base-piece, centrally between its ends, with a right-angularly-disposed straight arm having closely 25 adjacent parallel members and a loop at its extremity.

In the drawings, Figure 1 is a perspective view of a rein-holder embodying the herein-described design. Fig. 2 is a front view 30 thereof. Fig. 3 is a plan view.

Referring to the accompanying drawings, the numeral 1 designates the base-piece of the body of the rein-holder. This base-piece is longitudinally curved and is provided centrally between its ends with a right-angularly-disposed straight arm 2, projected laterally therefrom, and having closely adjacent parallel members 3, meeting in a rounded loop 4 at the extremity of the arm. The longitudinally-curved base-piece 1 is bent upon 35 itself at its opposite ends to form the opposite substantially **U**-shaped bends 5, which bends 5 are continued into the reversely-disposed ovoidal loops 6, lying in the same plane as the bends 5 and having terminal extensions 40 45 7, provided with looped feet 8, lying substantially in the plane of the base-piece 1.

What we claim is—

The design for a rein-holder, herein shown and described.

In testimony that we claim the foregoing as our own we have hereto affixed our signatures in the presence of two witnesses.

DAVID R. SAUNDERS.
JACOB M. LEE.
